Primary Examiner — Brian N Vinson(74) Attorney, Agent, or Firm — Carrithers Law Office PLLC(57) CLAIM

The ornamental design for a tissue box stand, as shown and described.

DESCRIPTION

FIG. 1 is a perspective view of the tissue box stand showing my new design;

FIG. 2 is a front view thereof;

FIG. 3 is a rear view thereof;

FIG. 4 is a left side view thereof;

FIG. 5 is a right side view thereof;

FIG. 6 is a plan top view thereof; and,

FIG. 7 is a plan bottom view thereof.

The broken lines showing the base of the stand are for illustrative purposes only and form no part of the claimed design.
